DESIGN FOR A COMBINATION CIGARETTE
HOLDER AND ASH RECEPTACLE OR SIM-ILAR ARTICLE

Jeannette Davis, West Los Angeles, Calif.

Application October 23, 1948, Serial No. 149,262

Term of patent 14 years

(Cl. D85—2)

To all whom it may concern:

Be it known that I, Jeannette Davis, a citizen of the United States, residing in West Los Angeles, in the county of Los Angeles, State of California, have invented a new, original, and ornamental Design for a Combination Cigarette Holder and Ash Receptacle or Similar Article, of which the following is a specification, reference being had to the accompanying drawing, forming a part thereof.

Fig. 1 is a perspective view of a combination cigarette holder and ash receptacle or similar article showing my new design with the intermediate flap portion removed therefrom for convenience of illustration.

Fig. 2 is a top plan view thereof, the article being fully opened and showing the intermediate flap covering the bottom ash tray portion of Fig. 1.

Fig. 3 is a top plan view of the same shown in closed position.

Fig. 4 is a side view of Fig. 3.

Fig. 5 is a sectional view taken along the line 5—5 of Fig. 2. The essential features of my design reside in the portion shown in solid lines.

I claim:

The ornamental design for a combination cigarette holder and ash receptacle or similar article, as shown and described.

JEANNETTE DAVIS.
